UNITED STATES PATENT OFFICE.

LAWRENCE C. MOONEY, OF MONTGOMERY, ALABAMA.

CROSS-TIE FOR RAILWAYS.

1,076,690.

Specification of Letters Patent.

Patented Oct. 28, 1913.

Application filed March 13, 1913. Serial No. 754,119.

To all whom it may concern:

Be it known that I, LAWRENCE C. MOONEY, a citizen of the United States, residing at Montgomery, in the county of 5 Montgomery and State of Alabama, have invented new and useful Improvements in Cross-Ties for Railways, of which the following is a specification.

This invention relates to railroad cross-ties and is designed to be relatively less expensive and more practicable than cross-ties now in common use.

The object of this invention is to provide a cross-tie made principally of cement concrete and strengthened by a longitudinal bar of metal embedded therein and extending substantially from end to end of the tie, said bar having a cruciformed cross-section throughout the greater part of its 20 length with an enlarged portion near each end as wide as the cross-tie, but of less height to serve as supports for the rails. Within the enlarged portions of the bar are horizontal chambers or pockets open at one 25 end only to receive blocks of wood or other suitable material capable of holding the rail spikes which are driven thereinto through holes formed in the top of said enlarged portions. As the enlarged portions or 30 pockets have the same width as the cross-tie and extend to the top thereof they are not covered on their ends and top with concrete but lie in the same plane respectively as the vertical sides and top of the tie. The concrete forming the body of the tie is partly 35 divided by the enlarged portions into three main sections, one section extending between the portions or pockets, and a section extending from each pocket to the end of 40 the cross-tie. Beneath each pocket is a relatively thin layer of concrete connecting the middle section with the end sections, within each of which layers is embedded a reinforcing cradle the ends of which extend up 45 into the body of the adjacent sections and add strength to an otherwise relatively weak portion of the cross-tie. The cruciform strengthening bar extends between the pockets and from each pocket toward the 50 ends of the tie and serve to bind the concrete sections to the metal pockets or enlarged portions and thereby form a strong, rigid and time resisting structure.

Another object of the invention is directed to a novel rail fastening device forming a part of the cross-tie. By means of

this device or rail chair, rails are held rigidly in position and prevented from moving laterally on the cross-ties, overturning, or loosening and drawing the spikes by the 60 weight and lateral pressure of passing trains.

With this and other objects in view the invention consists of the novel construction, combination and arrangement of parts hereinafter described and claimed and illustrated in the accompanying drawings, in which,

Figure 1 is a top plan view of the improved cross-tie with a portion of two rails 70 secured thereto. Fig. 2 is a perspective view of the interior strengthening or reinforcing bar of the cross-tie. Fig. 3 is a vertical longitudinal section of the cross-tie. Fig. 4 is an enlarged end view of the strengthening 75 bar. Fig. 5 is a cross-sectional view on the line 5—5 of Fig. 2. Fig. 6 is a similar view on the line 6—6 of the Fig. 3. Fig. 7 is a longitudinal sectional view on the line 7—7, Fig. 1, said figure and Figs. 4, 5 and 6 being on the same scale. Fig. 8 is a plan view of a portion of a railroad track showing the manner of laying the same and securing the rails in their chairs against lateral movement and loosening of the spikes. 85

In the drawings, wherein like reference characters are used to indicate like parts in all of the figures, A indicates the cross-tie as a whole having substantially the same length, width and height as cross-ties now 90 in common use and made principally of cement concrete or other suitable plastic material. In the center of the tie is a longitudinal strengthening member or beam 10 made of metal of cruciform cross-section 95 and extending from end to end of the tie. Near each end of said member is an enlarged portion 11 projecting above, below and laterally beyond its edges as shown. These enlarged portions are made hollow to 100 form horizontal chambers or pockets 12 open at one end on the side of the tie as shown in Figs. 2 and 6 into which pockets or chambers are tightly fitted blocks of wood or other suitable material capable of 105 holding rail spikes when driven thereinto.

The strengthening or reinforcing member 20 comprises a vertical rib 13 and a horizontal rib 14 intersecting each other to form the cruciform structure above mentioned, 110 said member being cast integral with the enlarged portions 11. The horizontal ribs

14 where they join the portions or pockets 11 are widened as at 15 to give strength to the tie and resist lateral strain. Between said widened portions 15 of the member 5 10 and the sides of the enlarged portions 11 are a plurality of ribs 16 which serve as braces between the member 10 and the enlarged portions and also firmly bind and anchor the concrete of the tie to the metal 10 reinforce. The ends of the strengthening member 10 terminate in vertical plates 17 which serve as anchors for the concrete sections forming the ends of the ties.

Perforations 18 are formed in the enlarged 15 portions or pockets 11 near the top and bottom walls of the same and transversely thereof, but longitudinally of the tie, in which perforations are seated bars 19 extending from one pocket to the other and 20 fastened in position against the sides of the pockets which when made with inclined walls as in the drawings has lugs 20 cast thereon. The number of bars may vary 25 according to requirement, in the drawings, two are shown on the upper side of the tie and two on the lower side. In addition to the bars 19 are other reinforcing rods 21 which extending from end to end of the tie through holes 22 in the enlarged portions 30 11 the ends of these rods being bent into the form of hooks as shown to more firmly anchor them in the concrete of the tie. The strengthening member 10 with the bars 19 and reinforcing rods 21 are placed in a suitable 35 mold and the latter filled with concrete and packed around the parts, the concrete incasing the whole of the strengthening member and the sides and bottom of the enlarged portions 11. The ends of the enlarged 40 portions are not covered with cement, they lying in the same plane as the vertical sides of the tie. The tops of said portions are also free of cement and lie in the plane of the top of the tie, the concrete just covering the tops of the lugs 20 and the ribs 16.

The cross-tie constructed as described comprises three main concrete sections, a middle section 23 and two end sections 24 and 25 connected to the central section 23 50 by a thin layer of concrete 26 beneath the enlarged portions 11. Were not some means provided for strengthening the thin layers 26 these parts would prove an element of weakness in the tie. This weakness, however, 55 is overcome by embedding within the concrete forming the layers 26, reinforcing cradles 27 which extend longitudinally of the tie for a short distance beneath the enlarged portions 11 and then incline upwardly, their 60 ends terminating in the body of the tie below the strengthening member 10. The ends of the cradles are bent upon themselves to form hooks which serve as anchors for the purpose of more securely suspending 65 said cradles in the concrete.

The top surfaces of the enlarged portions or pockets 11 form rail seats and are provided with suitable fastening devices or chairs for holding the rails. These chairs are alike on both pockets, so one only need 70 be described. The chair comprises a rib 28 projecting up from the top of the pocket from end to end thereof, across the tie with an undercut groove 29 in one side shaped to fit one side of the base of a rail B and hold 75 the rail firmly on its seat. The other side of the rail base is held in place by a key 30, as long as the rib 28, having an overhanging lip 31 on one side to overlie the rail base, and a dove-tailed foot 32 slidable in 80 a channel 33 of like shape in the top of the pocket 11 entirely across the tie. Holes 34 are made in the rib 28, key 30 and top of the pocket through which spikes 35 are driven into the wooden blocks 4 in the pockets. The spikes used differ from the ordinary rail spikes by having a shoulder 36 on one side a short distance below the head which when driven home, bear on the base of the rail and prevent it creeping. The heads 90 of the spikes bear at the same time on the rib and key.

Attention is called to the relative positions of the ribs 28 and keys 30 at the two ends of the cross-tie. At one end the rib 95 28 is on the outer side of the enlarged portion 11, or the side nearest the end of the tie, while at the other end the rib is on the inner side of the enlarged portion or the side away from the end. This is done to 100 permit the rails being held in position by the chairs with positive security from spreading, overturning or loosening the spikes by the manner of laying the track.

Fig. 8 shows a section of track comprising 105 two cross-ties with rails thereon. The ties when placed in position are arranged with their ends alternating. That is, one tie is placed with the fixed rib 28 at one end on the outside of rail B and at 110 the other end of the inside of rail B'. The next tie will have the sliding key at one end on the outside of rail B and at the other end on the inside of rail B'. The third tie will be placed similar to the first and 115 so on throughout the length of the track. This arrangement may be varied slightly by placing two or three ties alike, followed by two or three ties reversely arranged.

The cross-ties when placed on the ground 120 ready to receive the rails are without the keys 30 and do not lie with their ends in line as in Fig. 8, but are offset, the ends of alternate ties projecting, so that the rails may be supported on the ties at that side 125 of the ribs 28 in which are the grooves 29. Then by means of a pinch bar or other tool, the ties are forced endwise toward the rails until the grooves 29 closely embrace the bases thereof, after which the keys 30 are 130

slid into place, and the spikes driven. By this plan of track laying, each rail is firmly held in upright position by the overhang of the rib 28 and key 30 fitting closely upon the base of the rail. The ribs being integral with the enlarged portions or seats 11, and the keys firmly mounted therein by dovetailed connections, the weight of heavy trains, especially when on curves 10 tending to spread the rails and overturn them by the lateral pressure thereon due to centrifugal force, is entirely prevented and the rails stand firmly in place until worn out. The keys 30 in addition to their dovetailed connecting feet 32 and the spikes 35 for preventing the rails lifting them when trains are passing, each have a bead 38 on the side opposite the lip 31 that bears on the top of the pocket 11 and gives the key 15 greater support and acts as a brace therefor.

The reinforcing beam or member 10 is made of cruciform cross-section to give greater strength to the tie to resist vertical strains without adding excessive weight and bulk thereto. The rib 13 disposed vertically, adds greatly to the strength of the cross tie and prevents it from breaking when laid on ground that affords uneven support.

30 What I claim is,—

1. A railroad cross-tie comprising a concrete body having a metallic strengthening member of cruciform cross-section embedded therein and extending from end to end 35 of the tie, said member having enlarged portions formed adjacent the ends thereof and integral therewith on which the rails are seated, and a plurality of small strengthening ribs between the cruciform member and the enlarged portions.

2. A railroad cross-tie comprising a concrete body having a metallic strengthening member of cruciform cross-section embedded therein and extending from end to end 45 of the tie, said member having enlarged portions formed adjacent the ends thereof and integral therewith of less height than said tie and extending from end to end of the tie, said member having enlarged portions formed adjacent the ends thereof and integral therewith of less height than said tie and extending from side to side thereof, said enlarged portions each having a pocket therein open on one side, cushion blocks 50 tightly fitted in said pockets, and a rail chair on the top of each enlarged portion having a removable side.

55 3. A railroad cross-tie comprising a concrete body having a metallic strengthening member of cruciform cross-section embedded therein and extending from end to end of the tie, said member having enlarged portions formed adjacent the ends thereof and integral therewith of less height than said tie extending from side to side thereof.

and flush with its top, a plurality of small strengthening ribs between the cruciform member and the enlarged portions, reinforcing bars between the enlarged portions, reinforcing rods extending through said portions from end to end of the tie and a reinforcing cradle beneath the enlarged portions.

4. A railroad cross-tie comprising a metallic strengthening member of cruciform cross-section substantially as long as the tie and having near each end an enlarged portion to support the rails, a concrete body having parallel vertical sides and parallel bottom and top wholly incasing the cruciform part of said strengthening member and the sides and bottom of the enlarged portions, the ends and tops of said portions being flush respectively with the vertical sides and top of the concrete, and a reinforcing member embedded in the thin layer of concrete beneath each enlarged portion with upwardly inclined ends extending into the body of the tie.

5. A railroad cross-tie comprising a concrete body having a metallic strengthening member of cruciform cross-section embedded therein and extending from end to end of the tie, said member having enlarged portions formed adjacent the ends thereof and integral therewith on which the rails are seated, said enlarged portions each having a pocket therein open on one side, cushion blocks tightly fitted in said pockets, and a rail chair on the top of each enlarged portion having a removable side, one of said removable sides being on the outside of one rail and the other removable side on the inner side of the other rail.

6. A railroad tie comprising a concrete body having a metallic strengthening member of cruciform cross-section embedded therein and extending from end to end of the tie, said member having enlarged portions formed adjacent the ends thereof and integral therewith on which the rails are seated, a fixed rib on each enlarged portion extending across the tie in one side to receive a rail base, and a removable key on said enlarged portion to coöperate with said grooved rib for holding a rail, one of said keys being on the outside of one rib and the other key on the inside of the other rib.

7. A railroad cross-tie comprising a concrete body having a metallic strengthening member of cruciform cross section embedded therein and extending from end to end of the tie, said member having enlarged portions formed adjacent the ends thereof and integral therewith on which the rails are seated, said enlarged portions each having a pocket therein open on one side, cushion blocks tightly fitted in said body, a fixed transverse rib on each enlarged portion hav-

ing a groove in one side to receive a rail base, a removable key slideable transversely in a channel in said enlarged portion having an overhanging lip to coöperate with said grooved portion for holding a rail, and a bead on the side of the key opposite said rib to assist in sustaining said key in position, said rib, key and enlarged portion having holes therethrough for rail-holding

spikes which are driven into the cushion 10 blocks.

In testimony whereof I have hereunto set my hand in presence of two subscribing witnesses.

LAWRENCE C. MOONEY.
